UNITED STATES PATENT OFFICE.

JOSEPH ESCHER, OF PITTSBURGH, AND JOHN NAGY, OF WEST VIEW, PENNSYLVANIA,
ASSIGNORS TO JAMES H. MATTHEWS & COMPANY, OF PITTSBURGH, PENNSYLVANIA,
A CORPORATION OF PENNSYLVANIA.

DIE-HOLDER.

1,214,662.

Specification of Letters Patent. Patented Feb. 6, 1917.

Application filed July 10, 1916. Serial No. 106,377.

To all whom it may concern:

Be it known that we, JOSEPH ESCHER, residing at Pittsburgh, in the county of Allegheny and State of Pennsylvania, and JOHN NAGY, residing at West View, in the county of Allegheny and State of Pennsylvania, both citizens of the United States, have invented or discovered certain new and useful Improvements in Die-Holders, of which improvements the following is a specification.

Our invention relates to improvements in die-holders such as are employed in various implements and machines for printing and stamping signs and characters, legible, intelligible, decorative, or otherwise, upon suitable surfaces.

The invention is illustrated in the accompanying drawings, of which—

Figure 1 shows in perspective a die-holder such as is employed in a stamping machine, or for use by hand, equipped with dies, and embodying our present invention; Fig. 2 is a view of this same die-holder with its dies in place, shown in vertical section; and Fig. 3 is a view in transverse section, the plane of section being indicated by the line III—III, Fig. 2. The die-holder of Figs. 1-3 is a holder for a series of dies arranged in curved line for stamping upon a plane surface. Fig. 4 shows in side elevation, and Fig. 5 in vertical section a die-holder with dies attached, embodying our invention, and serviceable for stamping upon a curved surface. Fig. 6 is a view in detail, corresponding to Fig. 3 and showing a minor variation in construction.

In Letters Patent 1,078,601, granted November 11, 1913, to J. H. Matthews, a die-holder is shown and described which is capable of receiving and carrying a plurality of dies arranged in succession; the dies are, as the specification explains, identical in all respects, except only in their character-bearing stamping faces, and are accordingly replaceable and interchangeable in their mounting in the die-holder. The die-holder of the said patent is provided with a lock for the dies when in place in the holder, such lock being operative to alternately secure and release the entire row of dies simultaneously. The die-holder of the patent referred to is designed to receive and carry a row of dies arranged in straight-line formation.

Our present invention, though not necessarily so specifically limited, finds peculiar applicability in die-holders designed and intended to carry a row of dies arranged in a formation which is not a straight-line formation; as, for example, a row of dies arranged in curved formation in horizontal plane, for stamping a succession of characters in curved line upon a plane surface; or, again, a row of dies arranged in curved formation in vertical plane, for stamping a succession of characters upon a rounded surface. Figs. 1-3 of the drawings show the former arrangement, Figs. 4 and 5 the latter.

Referring first to Figs. 1-3, the die-holder is indicated at 1; it is provided with a die-seat 2 which, as best shown in Fig. 3, is curvilinear when viewed in transverse section, and is adapted to receive a succession of dies, d, d, d, etc., identical in shape of body, severally removable and interchangeable, and adapted when assembled and applied to enter and fill the die-seat. Each die is provided with a notch, n, adapted to receive the locking means. The lock consists of a member 3, formed conveniently as a leaf spring with an inturned die-engaging end 4, and secured at its opposite end to the body of the die-holder, all as shown in Figs. 1 and 2. Normally this lock stands in the position shown in Fig. 2, its die-engaging end protruding from the wall of the die-seat and (when the dies are in place) entering the notches n in the bodies of the dies and so securing them in place.

A bolt 5 which extends through the body of the die-holder is normally held by the spring 6 in the position shown in Fig. 2, with one end adjacent the inner face of locking member 3 at a point remote from the point at which member 3 is secured to the die-holder, and the other end extending beyond the face of the holder. The protruding end of bolt 5 may be pressed inward (that is, to the right, Fig. 2) against the tension of spring 6, and in such movement the member 3 is engaged and forced outward (to the right). In that movement the die-engaging end 4 of member 3 is withdrawn from die-engaging position, into the wall of the die-seat, and the die-seat is left free and unobstructed for removal, exchange, and insertion of dies. When knob 3 is released from inward pressure, spring 6

carries it again to the position shown in Fig. 2, and the locking member, thus released, resumes again its normal die-engaging position. Fig. 2 shows bolt 5 riveted to member 3, and manifestly in such particular construction the resilience of spring 6 may be relied on, not only to shift the bolt, but also to bring or assist in bringing member 8 back to locking position.

10 From the foregoing explanation it will be manifest that, if desired, the locking member may be repressed and the die-seat left entirely unobstructed while the dies are being moved, and so the lock may be guarded 15 from harm consequent upon oft-repeated blows from entering dies; and, on the other hand, it will be manifest that, by a proper shaping of contacting surfaces, the locking member, while securely holding the dies 20 against accidental withdrawal, may be made to recede in response to pressure from the entering dies to allow the dies to come to their place, whereupon it will spring forward to enter notches *n* and secure the dies. 25 This end may be attained by forming lock and die with the complementary inclined faces *a* and *b* shown in Fig. 6.

As shown in Fig. 3 the die-engaging portion 4 of the lock is curvilinear, corresponding in this respect to the shape of the die-seat and to the formation of the row of seated dies; and it will further be observed that the die-engaging portion is preferably formed as a succession of prongs, corresponding in number and spacing to the dies 35 which the holder is designed and intended to carry.

Referring now to Figs. 4 and 5, it will be noted at a glance that the row of dies is 40 curved when viewed in vertical elevation or section; that, as before, the dies *d* are in all respects (except of course in their stamping faces) identical and are freely interchangeable. To this end the die-seat *2^a* may 45 be regarded as a plurality of individual die-seats, arranged in radial grouping and of such depth as to bring the faces of the inserted dies to the desired relative positions and the locking notches in the dies to position 50 for engagement by the lock. The die-engaging end of the member *3^a* is correspondingly arc-shaped. Manifestly, the holder of Figs. 4 and 5, when equipped with dies is adapted to stamp a rounded surface, 55 in this instance a concave surface.

We have in the foregoing description ex-

plained that our invention is peculiarly applicable to a die-holder for a row of dies arranged otherwise than in straight-line formation; we have described it as applied to 60 rows of dies arranged in approximately true curves; it will be understood that the advantages realized in connection with this curvilinear arrangement will obtain equally well in any arrangement which is a departure 65 from straight-line succession. Certain of the ensuing claims contain the phrase curvilinear or its equivalent, and by that phrase we mean to include as within the scope of the claims departures from straight- 70 line configuration, even though the lines be not, precisely speaking, curves.

We claim as our invention:

1. In a die holder provision for seating and carrying a plurality of dies, and a 75 spring-impelled latch capable of movement to protrude from and recede within the walls of said die-seat, said latch including a succession of prongs corresponding in number to the number of dies which the said die-seat is adapted simultaneously to receive.

2. In a die-holder provision for seating and carrying a plurality of dies in curvilinear arrangement, and a spring-impelled 85 latch capable of movement to protrude from and recede within the walls of said die-seat, said latch including a succession of prongs corresponding in number to the number of dies which the said die-seat is adapted simultaneously to receive, 90 said succession of prongs arranged in a curved line corresponding to the curvilinear arrangement of the seated dies.

3. In a die-holder provision for seating 95 and carrying a plurality of dies in curvilinear arrangement, and a spring-impelled latch capable of movement to protrude from and recede within the walls of the die-seat, said latch including a succession of prongs 100 corresponding in number and spacing to the number and size of the dies which the said die-seat is adapted simultaneously to receive.

In testimony whereof we have hereunto 105 set our hands.

JOSEPH ESCHER.
JOHN NAGY.
